UNITED STATES PATENT OFFICE.

LOUIS M. EVANS, OF ALEXANDRIA, VIRGINIA, ASSIGNOR TO THE GOVERNMENT OF THE UNITED STATES.

POLE-CHANGING APPARATUS.

1,273,773.

Specification of Letters Patent. Patented July 23, 1918.

Application filed April 11, 1917. Serial No. 161,311.

To all whom it may concern:

Be it known that I, LOUIS M. EVANS, a citizen of the United States, residing at Alexandria, in the State of Virginia, have 5 invented certain new and useful Improvements in Pole-Changing Apparatus, of which the following is a specification.

This invention relates primarily to a current reversing transmitter or relay for use 10 in connection with telegraph, cable, radio or other systems, where it is particularly desirable to reverse the polarity of the applied current for each succeeding electrical impulse, as for example, in transmitting the 15 successive units of Morse alphabets or similar characters, and it may also be employed in connection with any other electrical circuits where alternate contacts are desired, even if it is unessential to reverse the polarity.

As an example of the practical utility of the invention, it may be stated that, as is well known, a long transmitting electrical line, such as a submarine cable, is much 25 more effective if the polarity is reversed for each succeeding impulse, and one of the important objects of the present invention is to provide mechanism for thus securing these successive reversals, said means being independent of the outgoing or transmitted current which, if utilized, creates a drag that results in slow operation. In other words, the present mechanism is entirely independent of any previous conditions of the circuit controlled thereby, so that a positive 35 action is secured under strictly local conditions and by local means that permits high speed transmission.

In the accompanying drawings—

40 Figure 1 is a view in elevation of the preferred embodiment of the invention, with unessential parts broken away,

Fig. 2 is a diagrammatic view,

45 Fig. 3 is a detail diagram to indicate an arrangement for securing a reversal of polarity.

Similar reference numerals designate corresponding parts in all the figures of the drawings.

50 In the embodiment disclosed, a suitable base 4 is employed, on which are mounted standards 5 connected by a cross bar 6. Mounted on the standards are two sets of electro-magnets, respectively designated 7

and 8, and 9 and 10, these magnets being 55 disposed in opposing relation and spaced apart to permit between them the location of an armature 11 that is pivotally mounted at its lower end, as shown at 12. This armature may be termed a pole-reversing device or member, its upper end being movable alternately into engagement with contact elements 13 and 14 disposed on opposite sides thereof. The said armature is, however, normally held in a central or neutral position out of engagement with the contact elements 13 and 14 and equidistant from the cores of the electro-magnets by centering springs 15.

A suitable source of electrical energy is 70 shown at 16, and is included in a circuit that includes the electro-magnets 7, 8, 9 and 10, said circuit also including a suitable circuit controller 17, which is illustrated in the form of an ordinary make and break 75 transmitting key. The electro-magnets each have two sets of windings, the windings for the magnet 7 being designated 7^a and 7^b, the windings for the electro-magnet 8 being correspondingly designated 8^a and 8^b, the 80 windings for the magnet 9 being illustrated at 9^a and 9^b, and the windings for the magnet 10 being designated at 10^a and 10^b. Tracing out the circuit from the battery 16, a line 18 leads from one pole 85 thereof to the winding 8^a and thence to the winding 7^a by the connection 19. From the winding 7^a, an electrical connection 20—21 is made with the winding 8^b, which in turn, is in series through the connection 22 with 90 the winding 7^b. The winding 7^b is connected, as shown at 23 and 24 with the winding 9^b, and the winding 9^b has an electrical connection 25 with the winding 10^b. The winding 10^b has an electrical connection 95 26—27 with the winding 9^a, the winding 9^a has an electrical connection 28 with the winding 10^a; and the winding 10^a is electrically connected to the key 17 by the wire 29. The contact element of said key is electrically connected to the other pole of the battery 16, as shown at 30. It will thus be seen that all the windings of all the electro-magnets are in series with the battery 16, and therefore when the key 17 is closed, it 105 will be evident that current will pass through all the windings, and but for the mechanism hereinafter explained, the elec-

tro-magnets would be equally energized so that the armature 11 would remain in its neutral position.

Pivotaly mounted, as shown at 31, is a 5 jockey 32 having its upper end in the form of a yoke 33 provided with inset projections 34 that are located on opposite sides of a lug 35 projecting from the armature 11. This jockey carries an electrical contact in 10 the form of a leaf spring 36 secured at its upper end to the jockey, the lower end being free and arranged to contact either with an element 37 or an element 38 mounted on opposite sides of the same. The element 37, 15 as shown in Fig. 2, is electrically connected by a wire 39 with the wires 26—27, and the contact element 38 is in like manner connected with the wires 20—21 by a wire 40. The spring 36 in turn is electrically connected, as shown at 41 with the wires 23—24, and as a result, it will be seen that the spring 36 and contact element 37 constitute a short 20 circuiting device for the coils 9^b and 10^b when the jockey is in one position, and 25 when it is in the other position, the spring 36 and contact element 38 constitute a short circuiting device for the coils 7^b and 8^b. The lower end of the jockey is adapted to be held in either of its extreme positions by 30 a roller 42 that rides beneath the lower end of said jockey, which is pointed for the purpose, this roller being carried by a suitable spring 43. This mechanism may be generally termed an automatic circuit controller. 35

Referring now to Fig. 3, there is illustrated the end of a cable at 44, which cable is shown as electrically connected at 45 with the armature 11. The contact element 13 40 has an electrical connection with one pole of a battery 45^a, the other pole being grounded at 46. The electrical contact element 14 is connected with one pole of a battery 47, the other pole of which is grounded at 48. It 45 will thus be evident that when the armature 11 is in engagement with the contact element 13, a current of one polarity will pass through the cable 44, the other end of said cable being, of course, grounded and there 50 being a suitable receiving apparatus in the circuit thus produced. On the other hand, when the armature 11 is in engagement with the contact 14, a current of opposite polarity will pass through the cable 44. It will be 55 understood that this showing is made merely for the purposes of illustration, and may be varied in many well known ways.

Briefly described, the operation of the apparatus is as follows: With the parts as 60 shown in Figs. 1 and 2, the armature 11 as already explained is in the neutral position, due to the centering springs 15, and all the electro-magnets are deenergized. It will, however, be noted that as the spring 36 of 65 the jockey is in contact with the element 38,

the coils 7^b and 8^b are short-circuited. Consequently if the key 17 is operated to close the local circuit which includes the battery 16, all the windings of all the electro-magnets will be energized, with the exception of 70 windings 7^b and 8^b. The result is that the electro-magnets 9 and 10 are more powerfully energized than the electro-magnets 7 and 8, and as the armature is equidistant between them, said magnets 9 and 10 will overcome the power of the magnets 7 and 8 and 75 move the armature 11 to the right. As a result, the jockey 32 will be shifted to the opposite position, thereby breaking the short circuit through the windings 7^b and 8^b, and at the same time short-circuiting the windings 9^b and 10^b, while the magnets 7 and 8 thus become more strongly energized than the magnets 9 and 10; the armature is now closer to the latter magnets, 80 and they still have sufficient power to overcome the double power of the magnets 7 and 8 because of the distance between the latter and the armature 11. As soon as the local circuit is broken by opening the key 17, all 85 the magnets are deenergized and immediately the armature 11 returns to its central or neutral position, so that upon the succeeding operation of the key, the armature will move in the opposite direction. As already explained, when the armature moves to the right it engages the contact 14, and thus causes a current of one polarity to pass through the cable 44, while upon the succeeding operation, it will make engagement 90 with the contact element 13 and a current of opposite polarity will be transmitted. 95

From the foregoing, it is thought that the construction, operation and many advantages of the herein described invention will 105 be apparent to those skilled in the art, without further description, and it will be understood that various changes in the size, shape, proportion and minor details of construction may be resorted to without departing 110 from the spirit or scope of the invention.

Having thus fully described my invention, what I claim as new, and desire to secure by Letters Patent, is:—

1. In an instrument of the character described, the combination with pole-changing means, of a local circuit, a controller for the local circuit, and devices controlled by similar successive alterations in the condition of the circuit for alternately operating the pole-changing means in opposite directions and also effecting the alternate operation of said devices. 115

2. In an instrument of the character described, the combination with pole-changing means, of a local circuit, an automatic controller for the local circuit, a device for making and breaking the circuit, and means in the circuit and controlled by repeated similar operations of the device for effecting the 120 125 130

operation of the automatic controller and the alternate operation of the pole-changing means in opposite directions.

3. In an instrument of the character set forth, the combination with electrical pole-changing means, of mechanism for operating the pole-changing means, said mechanism including a local electric circuit independent of the circuit controlled by the pole-changing means, means for intermittently altering the condition of said local circuit, and means controlled by successive correspondingly alternations to intermittently operate the pole-changing means and cause successive change of polarity thereby.

4. In an instrument of the character set forth, the combination with pole-changing means, of a local circuit, an automatic controller for the local circuit, a device for making and breaking the circuit, including a contact element and a make and break device movable into and out of contact therewith, and means in the circuit and controlled by the automatic controller for alternately moving the pole-changing means on the successive engagement of the make and break device with said contact element.

5. In an instrument of the character set forth, the combination with pole-changing means including a shifting device, of mechanism for effecting a shifting movement of said device, including electro-magnetic means, a local circuit including the electro-magnetic means, means for making and breaking the local circuit, and means controlled by the shifting of the device for controlling the energization of the electro-magnetic means by the local circuit.

6. In an instrument of the character set forth, the combination with a pole-changing device, of electro-magnetic means for operating the same, a local circuit including the electro-magnetic means, means for making and breaking the circuit, and means operated by the pole-changing device and controlling the energization of the electro-magnetic means by the local circuit to cause said device to successively change the polarity when operated by the electro-magnetic means.

7. In an instrument of the character set forth, the combination with a pole-changing device having a back and forth movement and alternately effecting a change of polarity thereby, of opposing electro-magnets for alternately actuating the same, a local circuit, means for controlling said circuit, and means operating with the pole-changing device to alternately vary the conditions of the opposing electro-magnets by the local circuit and thereby respectively effecting the back and forth movement of the pole-changing device.

8. In an instrument of the character set forth, the combination with a pole-chang-

ing device having a back and forth movement, of opposing electro-magnets for alternately shifting the same, a source of electrical energy, means for connecting the source of electrical energy to the electro-magnets, including a circuit controller, and means actuated with the pole-changing device to alternately vary the conditions of the electro-magnets and cause successive back and forth movements of the pole-changing device upon the successive operations of the circuit controller.

9. In an instrument of the character set forth, the combination with oppositely acting electro-magnets, of a pole-changing member operated thereby respectively in opposite directions, a local circuit including the electro-magnets, a circuit controller, and means operating with the pole-changing member to automatically and alternately vary the conditions of the opposing electro-magnets to cause them to move the pole-changing member alternately in opposite directions and thereby alternately change the current controlled by the member.

10. In an instrument of the character set forth, the combination with oppositely acting electro-magnets having sectional windings, of a pole-changing member operated respectively in opposite directions thereby, a local circuit including the windings of the electro-magnets, a circuit controller, and means operating with the pole-changing member to automatically and alternately cut out certain windings of the electro-magnets to cause them to operate the pole-changing member alternately in opposite directions and thereby alternately change the current controlled by said member.

11. In an instrument of the character set forth, the combination with oppositely acting electro-magnets, of a swinging pole-changing member respectively operated thereby, pole-contact elements alternately engaged by said member, means for normally holding the member out of contact with both elements, a local circuit including both electro-magnets, means for making and breaking the circuit, and a device operating with the pole-changing member for controlling the condition of the magnets to alternately act upon the changing member as the local circuit is successively opened and closed.

12. In an instrument of the character set forth, the combination with spaced oppositely disposed electro-magnets, of an armature pivotally mounted therebetween, contact elements disposed on opposite sides of the armature and alternately engaged thereby upon the swinging movement of said armature, a local circuit including the electro-magnets, means for making and breaking the circuit, said electro-magnets having sectional windings, a device operating with the armature for alternately short-circuit-

ing certain of the windings of the opposite magnets, and means for normally holding the armature in neutral relation with respect to the magnets.

- 5 13. In an instrument of the character set forth, the combination with different pole-contact elements, of a circuit closer member movable back and forth between the two for alternately changing the current, means for
10 normally maintaining the member in a neutral position out of contact with both elements, an electrical circuit, means for altering the condition of the same from a normal condition, and means in said circuit for
15 automatically shifting the circuit closer member from the neutral position into contact with one element when the condition of the circuit is altered and into contact with the other element when the said condition is
20 again similarly altered.
14. In an instrument of the character set forth, the combination with spaced pole contact elements, of a circuit closer member movable back and forth between the two
25 for changing the current, means for normally maintaining the member in a neutral position out of contact with both elements,

an electrical circuit, means for altering the condition of the same from a normal condition, means for making and breaking the circuit, and means in said circuit for automatically shifting the circuit closer member from said neutral position alternately into engagement with the two contact elements upon the successive operation of the circuit making and breaking means.

35 15. In an instrument of the character described, the combination with pole-changing means, of electro-magnets for alternately operating the pole-changing means, a local circuit including said electro-magnets, a circuit controller for the local circuit, and means for automatically and alternately short circuiting different of said electro-magnets on the successive similar changes in condition of the local circuit by the controller thereof.

40 In testimony whereof, I affix my signature in the presence of two witnesses.

45 LOUIS M. EVANS.
